UNITED STATES PATENT OFFICE.

ALEXANDER M. ALEXANDRESCU, OF CLEVELAND, OHIO.

AUTOMATIC CARBURETOR.

Application filed November 5, 1924. Serial No. 747,945.

The present invention relates to improvements in automatic carburetors and has for an object to provide a carburetor having controls for producing a mixture susceptible of being regulated to extremely fine proportions of air and fuel and to accomplish this result by a mechanism that is automatic and reliable in operation.

Other objects of the invention are to provide improvements in the control of the air inlet; of the fuel nozzle and to provide a by-pass extending about the nozzle and throttle for the air whereby to automatically dilute the mixture in the manifold and to further serve the purpose of relieving the vacuum in the cylinders when the throttle is closed thus preventing oil from the crank case from being drawn up into the cylinder heads fouling the spark plugs, creating carbon deposits, reducing the power of the motor and producing obnoxious smoke at the exhaust pipe.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of an improved automatic carburetor constructed according to the invention.

Figure 2 is a vertical section taken on the line 2—2 in Figure 1.

Figure 3 is a horizontal section taken on the line 3—3 in Figure 2.

Figure 4 is an end view.

Figure 5 is also an end view from the opposite end of the carburetor and with certain parts broken away.

Figure 6 is a vertical section taken on the line 6—6 in Figure 4.

Figure 7 is a fragmentary side view showing the air inlet valve control, and

Figure 8 is a fragmentary sectional view showing on an enlarged scale a portion of the by-pass and its control valve.

Referring more particularly to the drawings the improved carburetor is composed of a shell or casing having in the lower central portion thereof the fuel chamber 9 in which the liquid fuel is maintained at constant level by the use of the float device indicated at 10, but which is not illustrated in detail as this float device is of well known con-

struction. At 11 is indicated the inlet for the gasoline or other liquid fuel to the chamber 9.

The chamber 9 is shown as a cup shaped reservoir having an open upper end secured against the shoulder 12 of the main carburetor shell. This main carburetor shell is formed with a nozzle post 13 having the internal bore 14 and the nozzle 15 fitting in the bore and being of smaller diameter than said bore whereby to provide a chamber about the nozzle for the circulation of air, which air is received through the perforation 16 in one side of the post, the post being provided with the duct 17 at its side communicating with the port 16. The duct 17 opens at its upper end upon the by-pass 18. The by-pass is shown in Figure 2 and includes the portion 18 which extends substantially horizontally, the vertical portion 19 which communicates with the inner end of the portion 18 and also opens at its lower end upon the float chamber 9 so as to receive the vapor therefrom. The by-pass further includes the second horizontal branch or portion 20 connecting with the upper part of the vertical intermediate portion 19. The outer ends of the passages 18 and 20 are closed by the clean-out plugs 21 and 22 respectively and adjacent its plugs are the ports 23 and 24, also showing in Figure 6.

The intermediate portion 19 of the by-pass is formed of differential diameters producing a shoulder and valve seat against the edge of which the conical valve 26 is adapted to close. This valve is provided just above with the head or flange comprising a number of radial fingers 25 separated a distance apart and acting as a guide for the valve to slide in the upper larger portion of the vertical part 19. The valve and head are carried upon the lower end of the stem 27 and the coil spring 28, wound about the stem is made use of to retain the valve in the closed position. It will also seek this position by gravity. An adjustment of the spring may be made through the hollow screw 29 which also forms a guide for the upper part of the stem 27. The screw 29 is screwed through the nut 30 which closes the upper end of the vertical part of the by-pass and gives access to the interior parts for removal, adjustment and repair.

Referring to Figure 6 the throttle or butterfly valve is indicated at 31 and the usual mechanism is employed to open and close the

same. This butterfly valve is arranged in the mixture passage 32 which connects with the manifold. The intake port 23 for the by-pass enters the passage 33 on the atmospheric side of the choke valve while the outlet port 24 of the by-pass enters the air passage 32 on the manifold of the throttle valve 31. The air inlet passage 33 and the mixture or carbureting passage 32 are in substantially horizontal alignment, and at their meeting point are intersected by the fuel nozzle 15. The fuel control valve is represented at 35 and may be screwed up or down toward or from the nozzle. The internal wall of the carburetor is shaped to direct the incoming air downwardly toward the nozzle and the air valve 34 is pivoted above the passage 33 and opens inwardly to a diagonal position to further deflect the air downwardly upon the nozzle. The air valve 34 is provided at its upper end with the tubular casing 36 fitting loosely about the control shaft 37. The shaft is provided with a set screw 38 extending therefrom and through the arcuate slot 39 of the casing 36.

In Figure 7 the shaft 37 is shown to project beyond the wall of the air passage and to be provided with the bell crank lever 40 held in the lower portion yieldingly by a coil spring 41. In this position the lug 42 of the bell crank lever engages the stop 43 on the casing. This is the condition of part shown in Figure 6, the set screw 38 being in an upper position and permitting the air valve 34 to be swung inwardly through an angular movement equal to the circumferential length of the slot 39. As a consequence greater suction in the motor will draw greater quantities of air through the air intake and the valve 34 may swing open to accommodate the maximum draft. The air intake may or may not be connected with a hot air source or with a device for preheating the air. The throttle valve operating device is indicated at 44 in Figure 1.

In the use of the device, the engine is started by pulling out the choke on the dash board. This choke is connected to the bell crank lever 40 and the air or choke valve 34 is closed when the choke pull rod is fully drawn out from the dash or instrument board. By drawing this pull rod out the bell crank lever 40 is rotated in a clockwise direction (see Figure 7) and the shaft and set screw 38 are made to move through the slot 39 and against the lower wall of said slot pushing the casing and air valve around until in the extreme left dotted line position shown in Figure 6, where the valve closes against the bottom wall of the air passage and no air is permitted to be drawn into the engine. The throttle valve 31 is opened generally to a rather wide extent and the starter is put in operation causing the motor pistons to move up and down and create

suction. This suction operates to draw air in through the by-pass inlet port 23 but the air cannot pass completely through the by-pass because the valve 26 is closed. The air then descends through the duct 17 and entering through the port 17 gets into the annular passage at the base of the nozzle 15. This air ascends and picks up the fuel from the nozzle passing on to the mixing nozzle 15 and to the intake manifold.

As soon as this mixture ignites in the motor and the motor gains momentum, a substantial suction is created which suction will lift the valve 26 from its seat to a greater or less degree in accordance with the speed of the motor and this of course is dependent upon the port area controlled by the throttle valve 31. In any event the valve 26 will open to some extent and air may then pass completely through the by-pass out the outlet port 24 and into the manifold where it will automatically mix with and dilute the mixture coming through the carbureting passage 32. A substantial saving in fuel is thus effected. After the motor has been sufficiently warmed, the choke control device is pushed in and the spring 41 will return the shaft and the set screw 38 to the upper position shown in Figure 6 leaving the choke or air valve 34 free to swing backwardly under the inrushes of air. The air thus admitted will pass across the nozzle and pick up fuel with which it will afterwards become thoroughly commingled in the mixing passage and the manifold. A dilution of this mixture will take place to a more or less extent and automatically by the air admitted through the by-pass.

When the throttle valve is closed preparatory to stopping, the suction in the cylinders is still present without being relieved by the entering fuel mixture and consequently a great difficulty with the present operation of motor vehicles is the fact that at this time oil is drawn from the crank case up past the pistons in the cylinder head where the oil fouls the plugs, creates carbon deposits and causes smoky exhausts. This suction is however relieved by the air which is freely admitted through the by-pass and which thus takes up this suction and prevents it from devolving upon the crank case.

The improved carburetor will be found to effect a considerable saving in gasoline and to afford quick starting.

It is obvious that various changes and modifications may be made in the details of construction and design of the above specifically described embodiment of this invention without departing from the spirit thereof, such changes and modifications being restricted only by the scope of the following claims.

What is claimed is:—

1. A carburetor comprising a casing hav-

ing a reservoir for fuel and air and carbureting passages communicating with one another, a fuel nozzle connecting with the chamber and with said passages, an air valve 5 in said air passage, a shaft for supporting said air valve for pivotal movement, a loose connection between said shaft and valve acting as a stop to hold said valve closed in one position of the parts and permit similar 10 movement of said valve in other positions, and means for rotating said shaft to close and permit opening of the valve.

2. A carburetor comprising a casing hav-

ing a fuel chamber and connecting air intake and carbureting passages, a throttle valve 15 in the carbureting passage, an air valve pivotally mounted in said air passage and adapted to deflect the air downwardly, a nozzle connecting with the fuel chamber and with said passages, and operating means 20 having a loose play connection with said air valve for maintaining the same open to a predetermined extent and permitting the free further opening of the air valve by increased suction in said intake passage.

ALEXANDER M. ALEXANDRESCU.
